UNITED STATES PATENT OFFICE.

EDGAR M. BOUTON, OF EAST PITTSBURGH, PENNSYLVANIA, ASSIGNOR TO WESTINGHOUSE ELECTRIC & MANUFACTURING COMPANY, A CORPORATION OF PENNSYLVANIA.

SYSTEM OF CONTROL.

Application filed October 7, 1921. Serial No. 505,982.

My invention relates to systems of control and it has particular relation to systems employed in connection with elevators, hoists and the like.

5 An object of my invention is to provide means for controlling the operating speed of alternating-current elevator motors which are subject to wide variation in loads.

10 Another object of my invention is to provide means for effecting accurate stops or landing with an elevator car, regardless of the skill of the operator.

15 Other objects of my invention will be more apparent upon reference to the following specification and appended claims.

It is well known to those familiar with elevator systems that the speed of an alternating-current motor cannot be controlled entirely by means of secondary resistance, 20 as employed in other applications where the motor is driving a load. In elevator service, there are times when the load in the elevator car is sufficient to "overhaul" the motor, in which case the secondary resistance is ineffective to control the motor speed.

High-speed alternating-current elevator systems commonly employ two-speed motors of special design, having high and low-speed operating windings. Such systems are 30 satisfactory in general but the motors are larger and more expensive than standard single-speed motors and are less flexible in operation than is the system which I propose.

35 I propose to employ a single-speed alternating-current motor with a system of control similar to that employed in connection with two-speed motors. The motor is connected, for normal operation, to a source of 40 supply of constant or normal frequency. For low-speed operation, the motor receives current at a reduced frequency from a rotary-converter or frequency changer. The rotary-converter is of a self-starting type 45 such as that described in United States Patent No. 1,235,583 to Friedrich W. Meyer and assigned to the Westinghouse Electric & Manufacturing Company. The motor is directly under control of the elevator operator by means of the usual car switch. To 50 eliminate the necessity of employing skilled operators, automatic controlling means is provided comprising a switching mecha-

nism, which, for convenience, is mounted on the car and is actuated by cams in the 55 hatchway. When the operator returns the car switch to its off position, for effecting a stop approximately level with the desired landing, he actuates a switch which continues the movement of the elevator car to 60 effect an accurate landing.

Door switches, commonly employed for another purpose, may be utilized to accomplish the operation described, or a manually operated switch or push button may, in 65 some instances, be more desirable. In the copending application of H. D. James, Serial No. 435,777, filed January 8, 1921, which has matured into Patent No. 1,448,407, assigned to the Westinghouse Electric & 70 Manufacturing Company, the details of such arrangement are described and they constitute no part of my invention.

The single figure of the drawing is a dia- 75 grammatic representation of circuits and apparatus embodying my invention.

A hoisting motor 1 is connected through reversing contactors 2 and 3, in normal operation, to line conductors 4, 5 and 6. A frequency changer 7, which is connected to 80 a source of energy through transformers 8 and 9, supplies energy, at low frequency, to the motor 1 for effecting low-speed operation. Contactors 11, 12 and 13 control the secondary resistor 14 of the hoisting motor 85 1. Contactors 15 and 16 respectively control the high and the low-speed operations. A relay 17 controls the short-circuiting of the secondary resistor 14 to effect acceleration of the motor. This relay constitutes 90 the subject-matter of the copending application of H. D. James, Serial No. 295,304, filed May 17, 1919, and assigned to the Westinghouse Electric & Manufacturing Company. 95

A relay 18 controls resistor sections 19 which are employed in the stator circuit of the rotary converter 7. A polyphase electromagnetic brake 21, of well-known design, is employed for maintaining the elevator car 22 at any desired landing. A relay 23 controls the operation of the brake magnet. A relay 24 prevents the starting of the hoisting motor until the rotary-converter is operated to deliver current at suitable frequencies. Overload protection is afforded 100 105

2
by a relay 25. The customary auxiliary controlling devices include car switch 26, hatch-way limit switches 27 and 28, door switches 29 and emergency switch 31. An auxiliary control switch 32 is located in the car and actuated by cams 33 located in the hatch-way.

It may be assumed that the frequency changer 7 is in operation and that the several switches and controlling devices occupy their respective illustrated positions.

The operating coil of the relay 37 is normally energized by a circuit extending from line conductor 4 through conductor 34, operating coil 46 of relay 37, door switches 29, conductor 47, switch 31, limit switches 28 and 27 and conductor 61 to line conductor 6. The relay 24 is normally closed, since its coil 48 is energized from the frequency changer 7.

In normal operation, the elevator car moves upwardly upon the actuation of the handle of the car switch 26 to the left, as viewed in the drawing, thereby establishing a circuit for the operating coil of the contactor 2 extending from line conductor 4 through conductor 34, contact members 35 and 36 of relay 37, contact members 38, 39 and 40 of the car switch, conductor 41, operating coil 42 of contactor 2, conductors 43 and 44, relays 24 and 25, conductor 45, switch 31, limit switches 28 and 27 and conductor 61 to line conductor 6. The contactor 2 closes to partially complete the primary circuits of the motor 1 for operation in the "up" direction.

In normal operation, the car switch is actuated to the extreme left, causing a relay 49, which may be termed the "transfer" relay, to establish a circuit for the operating coil of the high-speed contactor 15. The circuit for the operating coil of the transfer relay 49 extends from line conductor 4 through conductor 34, contact members 35 and 36, contact members 38, 39 and 51, of the car-switch conductors 52 and 53, coil 54, conductors 55 and 44 and relays 24 and 25 to line conductor 6, as previously traced.

The circuit for the operating coil of contactor 15 extends from line conductor 6 through conductor 61, switches 27, 28 and 31, relays 25 and 24, conductors 44 and 43, operating coil 56 of contactor 15, conductor 57, contact members 58 and 59 of the transfer relay 49 and conductor 34 to line conductor 4.

Upon the closing of contactor 15, current is supplied to the primary windings of the motor 1 as follows: from the conductor 6 through conductor 61, contactor 2, conductor 65, through primary windings of the motor 1 and out through conductor 66, coil 67, and conductor 68, contactor 2, conductor 69, contactor 15, and conductor 34 to line conductor 4. The primary windings are also

connected through conductor 71, coil 72, conductor 73 and contactor 15 to line conductor 5.

A circuit for the coil of brake relay 23 extends from line conductor 6 through conductor 61, interlock switch 62, attached to contactor 2, conductor 63, coil 64 and conductor 34 to line conductor 4. The brake relay 23 accordingly closes to effect the energization and release of the electromagnetic brake 21 simultaneously with the energization of the hoisting motor 1. Accelerating resistor 14 is connected, in the usual manner, to the slip rings 74, 75 and 76 of the motor 1 and is excluded from the secondary circuit by the successive closure of accelerating contactors 11, 12 and 13. The calibrating coil 77 of the accelerating relay 17 is connected across sections of the resistor 14 and is, therefore, subject to the value of the current traversing the secondary resistor, as measured by the drop in potential between the points of connection.

The holding coil 78 of the relay 17 effects the release of the relay contact fingers which are subsequently controlled by the calibrating coil 77. The holding-coil circuit extends from line conductor 6 through conductor 61, interlock 62 attached to contactor 2, conductor 63, coil 78, conductor 79, interlock 81 attached to contactor 15, conductor 52, contact members 51, 39 and 38, contact members 36 and 35, and conductor 34 to line conductor 4. Subject to the gradual drop in potential applied to calibrating coil 77, contact fingers 82, 83 and 84 successively engage contact members 85. The operating coils 86, 87 and 88 of accelerating contactors 11, 12 and 13, respectively, are successively energized by the engagement of contact members 82, 83 and 84 with contact members 85.

The contact members 85 are connected to line conductor 6 through conductor 63 and interlock 62 of the contactor 2. A circuit extends from contact finger 82 through coil 86 of contactor 11, conductor 79, interlock 81, conductor 52 and through the car-switch contacts 51, 39 and 38, as previously traced, to line conductor 4. Coil 87 of contactor 12 and coil 88 of contactor 13 are connected to line conductor 6 through interlock 89, conductor 79, interlock 81 and conductor 52. Circuits through coils 87 and 88 are completed through contact members 83, 84 and 85 to line conductor 6. The motor now operates at maximum speed, with the secondary resistor 14 short-circuited.

Contactor 91 is normally closed to connect the primary transformer windings 8 and 9 in circuit with the frequency changer 7. A circuit for the actuating coil of the contactor 91 extends from line conductor 4 through operating coil 92, conductor 45, switch 31, limit switches 28 and 27, and conductor 61 to line conductor 6. The frequency changer 130

7 is now operating at a reduced speed because of resistors 19 which are in circuit with its stator winding. The value of the resistors 19 is such as to provide current at a suitably reduced frequency so that the hoisting motor may be transferred from its high speed to its low-speed connections without producing an excessively sudden reduction in the motor speed.

10 To effect this change, the car switch 26 is moved towards its off position to disengage the contact member 51 from contact member 39. The operating coil 54 of the transfer relay 49 is now de-energized to effect the disengagement of contact members 58 and 59 and the opening of the contactor 15. The contact member 59 engages the contact member 93 to effect the energization of coil 94 of the low-speed contactor 16 by means of a circuit extending from line conductor 4 through conductor 34, contact members 59 and 93, conductor 95, coil 94, conductors 43 and 44, relays 24 and 25, conductor 45, switch 31, limit switches 28 and 25, 27 and conductor 61 to line conductor 6. The opening of high-speed contactor 15 interrupts the circuit for coil 78 of the accelerating relay 17 through interlock 81.

30 The contact fingers 82, 83 and 84 are returned to their inoperative positions to effect the opening of contactors 11, 12 and 13 and to reinsert starting resistor 14. The contactor 16 closes immediately after the opening of contactor 15 to establish low-speed connections for the hoisting motor 1 to the frequency changer 7. This circuit may be traced from conductor 96 through conductor 61, contactor 2, conductor 65, through one phase of the primary winding 10 of the motor 1 to conductor 66, coil 67, conductor 68, contactor 2, conductor 69 and contactor 16 to conductor 97. A motor terminal is also connected through conductor 71, coil 72, conductor 73 and contactor 16 to conductor 98. The contactor 18 is closed to exclude a portion of the resistor sections 19, from the stator circuit of the rotary-converter to effect an increase in the speed of the latter and a reduction in the frequency 50 of the current delivered to the hoisting motor. The circuit for the operating coil of the contactor 18 extends from line conductor 6, through coil 99, contact members 93 and 59 of the transfer relay 49 and conductor 34 to line conductor 4.

55 The closure of contactor 16 completes a circuit for energizing holding coil 78 of the accelerating relay 17. This circuit extends from line conductor 4 through conductor 34, contact members 59 and 93, conductor 95, interlock 101, conductor 79, coil 78, conductor 63, interlock 62 and conductor 61 to line conductor 6. Contact fingers 82, 83 and 84 of the accelerating relay 17 again operate to short-circuit resistor 14, as the ele-

vator speed is gradually reduced to a minimum. Resistor 14 limits the motor current during the slow-down period and thereby prevents too rapid change in torque and speed.

70

While the elevator is below the desired landing, and moving upward, the cam 33 is out of engagement with the switch 32, and the spring 103 causes the engagement of contact members 32 and 104. A circuit 75 exists, therefore, to maintain the contactor 2 closed after the car switch is in its "off" position. This circuit extends from line conductor 4 through conductor 34, contact members 35, 102, 32 and 104, conductor 41, 80 coil 42 of contactor 2, conductors 43 and 44 and relays 24 and 25 to line conductor 6, as previously traced.

Assuming that the elevator is about to stop at the desired landing, after the operator has released the master switch 26, he will actuate one of the door switches 29, interrupting the circuit through the coil 46 of the relay 37, thereby effecting engagement of contact members 35 and 102.

85

The car continues to move upward at a very slow speed until the cam 33 actuates the switch 32 to its inoperative position when the elevator is substantially level with the desired landing.

90

95 The separation of contact members 32 and 104 opens the circuit of actuating coil 46 of contactor 2, and the latter opens the circuit of the motor 1. The opening of interlock 62 connected to contactor 2 effects 100 the de-energization and application of brake 21.

If, for any reason, the car should travel beyond the desired landing, its motion will be reversed upon the operation of the cam to effect the engagement of contact members 32 and 105 to effect the closing of reversing contactor 3. The car is brought to rest upon its becoming level with the landing by reason of the switch 32 being actuated to its central or inoperative position to effect the opening of the motor circuits in a manner corresponding to that previously described.

105

The operation of the elevator downward is effected in substantially the same manner as is its upward movement, which will be readily understood by those familiar with the art. It is therefore considered unnecessary to trace the circuits which are completed by the actuation of the car switch in effecting the closure of the reversing contactor 3 and in repeating the functioning of the control system, previously described.

110

I have described an elevator system in which a standard single-speed hoisting motor is employed, together with a rotary-converter of small capacity relative to that of the hoisting motor. It will be recognized that, in practice, the rotary-converter is carrying load for a much shorter period, in the 115 120 125 130

cycle of operation of the elevator, than is required of the elevator motor.

With my system, it is possible to obtain very low operating speeds which are recognized as desirable for effecting accurate landings. It has been found desirable to automatically control the speed of the rotary-converter, as well as the secondary current of the hoisting motor, to insure smoothness of operation when transferring from high to low operating speeds. With the system which I have described, it will be found practical to operate alternating-current elevators at a much higher speed than has heretofore been advisable.

I claim as my invention:

1. The combination with an elevator car and an alternating-current hoisting motor therefor, of means for supplying energy at different frequencies, means for selectively varying the frequency applied to said motor, and electroresponsive means for insuring gradual change in the value of frequency to insure an accurate and smooth stop of the elevator car.

2. The combination with an alternating current motor, of a supply source of constant frequency, means for converting the frequency, a switch for connecting the motor selectively to the source of supply or to the converting means, manually operable means for initiating said change in motor connections and for varying the frequency of said converting means, and frequency controlled means for controlling the initial motor connections.

3. The combination with an elevator and an alternating-current hoisting motor, of a source of energy at constant and variable frequencies therefor, for operation of said motor at different speeds, a switch actuated by the elevator operator for effecting low-speed motor connections to further vary the value of the frequency, and means responsive to the frequency of said variable source for controlling said motor.

4. The combination with an elevator and an alternating-current hoisting motor, of a supply source of constant frequency therefor, means for converting the frequency to effect relatively low motor speed, a frequency relay for controlling the motor connections, a manually-operable switch for effecting low-speed motor connections to further vary the value of the frequency and means controlled by movements of the elevator car for effecting an accurate stop independently of the manually-operable switch.

5. The combination with an elevator car, an alternating-current hoisting motor therefor, and means for supplying energy at variable frequencies to said motor, of controlling means for said motor, a switch and electroresponsive means controlled in ac-

cordance with the position of the switch for varying the frequency, effecting the actuation of the car substantially to a floor level and for rendering the controlling means ineffective.

6. The combination with an elevator car, an alternating-current hoisting motor therefor and a source of energy, of controlling means for said motor, a variable frequency converter operated from said source for effecting a low motor speed, a door switch and a relay controlled in accordance with the position of the door switch for controlling the frequency, for effecting the actuation of the car substantially to a floor level and for rendering said controlling means inoperative when said door switch is open.

7. The combination with an alternating-current motor and a source of energy therefor, of controlling means, a frequency converter for effecting slow operating speed of the motor and means controlled in accordance with the value of the current and frequency supplied by said converter for controlling said motor.

8. The combination with an elevator car and a hoisting motor therefor, a supply source of normal frequency, electroresponsive means for reducing the frequency supplied to the motor, controlling means for selectively connecting the motor to operate on either normal or on reduced frequency, and current limiting means for controlling the secondary current of said motor and the value of the applied frequency substantially simultaneously with the motor connections.

9. The combination with an elevator car and a hoisting motor therefor, a supply source of normal frequency, means for reducing the frequency supplied to the motor, controlling means for said motor comprising a car switch for selectively connecting the motor to operate on either normal or on reduced frequency, current limiting means for controlling the secondary current of said motor and the value of the applied frequency substantially simultaneously with the motor connections, and a switch for effecting the actuation of the car substantially to a floor level independently of the car switch.

10. The combination with an elevator car and an alternating-current hoisting motor therefor, of controlling means for said motor, a switch on the car, a frequency converter controlled in accordance with the position of the switch for effecting slow operating speed of the motor independently of the controlling means, and means for preventing operation of said motor until the frequency supplied by the converter is of a predetermined value.

11. The combination with an elevator car, an alternating-current electric motor opera-

tively connected thereto and means for supplying energy at different frequencies to said motor, of a rheostatic controlling device for selectively determining and gradually changing the frequency applied to said motor, and means controlled by the position of the car for maintaining the circuits of said motor for operation at low speed when said controlling device is in its inoperative

position and said car is not level with an adjacent landing and for automatically interrupting the circuits of the motor when the car is substantially level with a landing.

In testimony whereof, I have hereunto subscribed my name this first day of October 1921.

EDGAR M. BOUTON.
